Primary Examiner—Antoine D. Davis*Assistant Examiner*—Patricia Palasik(74) *Attorney, Agent, or Firm*—Plevy, Howard & Darcy, PC(57) **CLAIM**

The ornamental design for a tire pressure gauge, as shown and described.

DESCRIPTION

FIG. 1 is a front view of a tire pressure gauge showing our new design;

FIG. 2 is a rear view thereof;

FIG. 3 is a left-side elevational view thereof;

FIG. 4 is a right-side elevational view thereof;

FIG. 5 is a top view thereof; and,

FIG. 6 is a bottom view thereof.

The matter shown in broken lines is shown for illustrative purposes only, and forms no part of the claimed design.

1 Claim, 5 Drawing Sheets
